INVENTOR

UNITED STATES PATENT OFFICE

95,275

DESIGN FOR A LADY'S COAT

Henry Mandelbaum, New York, N. Y.

Application January 23, 1935, Serial No. 55,024

Term of patent 3½ years

To all whom it may concern:

Be it known that I, Henry Mandelbaum, a citizen of the United States of America, residing in Manhattan, county of New York, and State of New York, have invented a new, original, and ornamental Design for a Lady's Coat, of which the following is a specification, reference being had to the accompanying drawing, forming part thereof, wherein,

I claim:

The ornamental design for a lady's coat, substantially as shown.

HENRY MANDELBAUM.
